THERMOSTAT KNOB CONSTRUCTION

Kenneth B. Dafforn and Russell I. Huffman,
Dover, Ohio, assignors to Knapp-Monarch
Company, St. Louis, Mo., a corporation of Mis-
souri

Application March 24, 1941, Serial No. 384,922

11 Claims. (Cl. 74—424.8)

Our present invention relates to a thermostat knob construction wherein a knob of Bakelite or similar molded material may be inexpensively connected in an operative manner to a thermostat adjusting screw without the necessity of molding inserts into the knob.

One object of the invention is to provide a connecting element between a thermostat adjusting screw and a knob which may be inexpensively fabricated in the form of a metal stamping and secured to the knob as by screws or the like, thus eliminating an expensive mold type of requiring means for holding an insert in proper position with respect to the mold while molding the knob.

Another object is to provide a washer which may be connected to the knob and slidably and non-rotatably associated with a thermostat adjusting screw extending from a sad iron shell or the like.

Still another object is to provide the connecting washer with a downturned stop lug which may cooperate with another stop lug formed on the sad iron shell.

A further object is to provide spring means to hold the knob closely adjacent the sad iron shell while the thermostat adjusting screw floats inwardly and outwardly as a result of its screw threaded character and rotation being imparted to the screw by the knob.

With these and other objects in view, our invention consists in the construction, arrangement and combination of the various parts of our device whereby the objects contemplated are attained, as hereinafter more fully set forth, pointed out in our claims and illustrated in the accompanying drawing. Although the invention is susceptible of a variety of embodiments, it is unnecessary to fully describe and illustrate more than one in order to give a full understanding of the invention both from its structural and functional standpoints. Accordingly, we have illustrated a preferred and desirable embodiment of the invention in the accompanying drawing, in which

Figure 1 is an elevation partly in section of a sad iron in which our thermostat knob construction has been employed;

Figure 2 is an exploded side elevation partly in section of the knob and thermostat adjusting screw, together with their associated parts;

Figure 3 is a sectional view on the line 3—3 of Figure 1;

Figure 4 is a plan view of the knob per se, and Figure 5 is an inverted perspective view of a special type of washer used in our construction.

In the accompanying drawing we have used the reference numeral 10 to indicate generally a sole plate and 12 a shell of a sad iron. A handle 11 is mounted on the shell 12 by means of front and rear supports 13 and 14.

The sad iron illustrated includes a bimetal element 15 which when heated to a predetermined degree bends downwardly, as shown, to permit a contact spring 16 to be separated from a contact spring 17 which it normally engages.

A stationary part 18 in the sad iron has a threaded bore 19 adapted to receive a thermostat adjusting screw 20. The screw 20 has an insulating button 20a on its lower end adapted to contact with the spring 17 and adjust it to thereby determine the temperature at which the contacts will be separated.

A knob 26 is provided for rotating the adjusting screw 20. A washer 22 is provided for connecting the knob with the adjusting screw. For this purpose, the washer 22 at its center has a splined perforation 24 adapted to coact with a splined shank 21 of the adjusting screw 20. This method of coaction permits sliding movement of the adjusting screw relative to the knob, but prevents any rotation of one relative to the other whereby both must rotate together.

The knob 26 is provided with a bore 34 and with a counterbore 34a. The washer 22 is adapted to fit in the counterbore 34a and to be secured therein by screws 25 extending through perforations 23 of the washer and into threaded sockets 25a of the knob. To additionally locate the washer in the counterbore, the washer is provided with notches 27 and 28 adapted to receive projections 30 and 31, respectively, of the knob in the counterbore.

The material that was initially in the notch 27 is bent downwardly to form a stop lug 28. The lug 28 enters an opening 28a formed in the shell 12 and is adapted to cooperate with a stop lug 28b extending inwardly from the edge of the opening. The knob 26 is thus limited to slightly less than one revolution of adjustment.

Within the bore 34 a spring 32 is provided. The spring 32 is interposed between the washer 22 and the head of a screw 33 threaded into a bore 33a in the upper end of the adjusting screw 20. The spring 32 tends to keep the knob 26 against the shell 12, yet permits the slight longitudinal movement of the adjusting screw, relative to the knob occurring as a result of rotation of the screw threaded into the member 18.

My knob construction is such that the necessity of molding inserts into the knob when it is formed

is entirely eliminated and the element 22 may be inexpensively formed as a stamping. Assembly involves merely the connection of the member 22 to the knob after the spring 32 has been inserted in the bore 34, the placing of the knob in position on the adjusting screw and the mounting of the screw 33 in position.

Another feature may be mentioned with respect to the spring 32. It will be noted that the spring is shouldered by reducing the diameter of the upper half thereof. Accordingly the lower half is retained between a constriction 34^b of the bore 34 and the washer 22 against displacement even though the screw 33 becomes lost. Normally of course the screw 33 is retained in position by being tight in the threaded bore 33^a of the adjusting screw 20 with compression of the spring 32 tending to keep it tight.

Some changes may be made in the construction and arrangement of the parts of our device without departing from the real spirit and purpose of our invention, and it is our intention to cover by our claims any modified forms of structure or use of mechanical equivalents which may be reasonably included within their scope without sacrificing any of the advantages thereof.

We claim as our invention:

1. In a knob construction, a knob of molded material or the like having a bore therethrough, a washer, screws for retaining said washer mounted against said knob, said washer having a splined perforation at its center, an adjusting screw having a splined shank entering said perforation and extending into said bore of said knob, a spring in said bore having one end against said washer, and a screw in said shank having a head against the other end of said spring.

2. In a thermostatic knob construction, a knob of molded Bakelite or the like having a bore therethrough, a counterbore in the bottom of said knob, a washer in said counterbore, means for retaining said washer mounted in said counterbore, said washer having a splined perforation at its center, a thermostat adjusting screw having a splined shank entering said perforation and extending into said bore of said knob, a spring in said bore having one end against said washer, and a screw in said shank having a head against the other end of said spring to urge said knob longitudinally of said shaft and to permit longitudinal movement of said adjusting screw through said perforation with the knob remaining operatively connected with the screw to rotate it.

3. A knob construction comprising a knob and means for connecting said knob with an adjusting screw or the like comprising a disc, screws for retaining said disc mounted on said knob, said disc having a splined perforation, an adjusting screw having a splined shank entering said perforation and extending into said bore of said knob, a spring in said bore having one end against said washer, and a screw in said shank having a head against the other end of said spring to urge said knob longitudinally of said screw.

4. In a thermostatic knob construction, a knob of molded material, having a bore therethrough, a counterbore in the bottom of said knob, a washer in said counterbore, screws for retaining said washer mounted in said counterbore, said washer having a splined perforation at its center, a thermostat adjusting screw having a splined shank entering said perforation and ex-

tending into said bore of said knob, a spring in said bore having one end against said washer, and a screw in said shank having a head against the other end of said spring to permit longitudinal movement of said adjusting screw through said perforation with the knob remaining operatively connected with the screw to rotate it.

5. A thermostatic knob construction comprising a knob, a washer having a notch in its periphery, said knob having a projection entering said notch, means for securing said washer to said knob, said washer having a splined perforation at its center to slidably and non-rotatably coact with said shank of said adjusting screw, said shank extending into said bore of said knob, and spring means interposed between said shank and said washer to retain said knob in position closely adjacent said shell and permit longitudinal movement of said adjusting screw relative to said knob as the knob is rotated for adjusting the screw.

6. A thermostatic knob construction comprising a knob of molded material or the like having a bore and a counterbore, a washer in said counterbore, said washer having a notch in its periphery and said knob having a projection extending into said counterbore and entering said notch, means for securing said washer in said counterbore, said washer having slidable and non-rotatable connection with the shank of said adjusting screw, said shank extending into said knob, and spring means interposed between said shank and said washer to urge said knob in a direction toward said shell.

7. A thermostatic knob construction comprising a knob of molded material or the like having a bore and a counterbore, a washer in said counterbore, said washer having a notch in its periphery and said knob having a projection extending into said counterbore and entering said notch, means for securing said washer in said counterbore, said washer having a splined perforation, a thermostat adjusting screw having a splined shank extending through a perforation in a sad iron shell or the like, said washer having a stop lug depending therefrom, said perforation of said shell having a cooperating stop lug extending inwardly from the edge of the shell perforation to limit rotation of said adjusting screw, said splined perforation of said washer slidably and non-rotatably coacting with said shank of said adjusting screw, said shank extending into said bore of said knob, and spring means interposed between said shank and said washer to retain said knob in position closely adjacent said shell and permit longitudinal movement of said adjusting screw relative to said knob as the knob is rotated for adjusting the screw.

8. A thermostatic knob construction comprising a knob having a bore and a counterbore, a washer in said counterbore having opposite notches, means for securing said washer in said counterbore, projections from said knob into said counterbore and entering said notches, said washer having an other-than-round perforation, a thermostat adjusting screw having an other-than-round shank slidably and non-rotatable in said perforation of said washer, and means to urge said knob in one direction longitudinally of said adjusting screw.

9. A thermostatic knob construction comprising a knob having a bore and a counterbore, a washer in said counterbore having opposite notches, means for securing said washer in said

counterbore, projections from said knob into said counterbore and entering said notches, said washer having a stop lug bent away from the knob at the bottom of one of said notches and having an other-than-round perforation adjacent its center, a thermostat adjusting screw having an other-than-round shank slideable and non-rotatable in said perforation of said washer, a shell for the thermostat and having an opening through which said adjusting screw extends, said opening receiving said stop lug and said shell having a cooperating stop lug extending inwardly from the periphery of said opening, and means to prevent dislocation of said knob from said adjusting screw.

10. A thermostatic knob construction comprising a knob having a bore, a washer secured to the bottom of said knob, said washer having an other-than-round perforation adjacent its center, a thermostat adjusting screw having an other-than-round shank slideable and non-ro-

5 tatable in said perforation, a shell for the thermostat and having an opening through which said adjusting screw extends, said bore of said knob having a constriction, a spring in said bore between said adjusting screw and said washer, said spring having an enlarged part retained between said constriction and said washer.

11. A knob construction comprising a knob having a bore, a washer secured to said knob, 10 said washer having a splined perforation at its center, an adjusting screw having a splined shank extending to slidably and non-rotatably coact with said washer, said shank extending into said bore of said knob, a spring interposed between 15 said shank and said washer to retain said knob in position, said spring being shouldered, and said bore having a constriction to coact with the shoulder thereof.
